UNITED STATES PATENT OFFICE

PUTNAM P. BICKNELL, OF ROCKLAND, MAINE

BUSH CHISEL

Application filed February 24, 1931. Serial No. 517,733.

This invention relates to bush chisels and particularly to an improved or novel type of these tools which are generally old and standard in the stone working industry. These tools have for many years been fitted with detachable cuts removably held in a head by which they could be directed against the surface to be worked.

Various efforts were made to improve the manner of holding the cuts so that they would be readily removable but firmly held and not subject to being loosened by the shocks and strains of the chisel when in use.

It was conceived that a system of wedging was desirable and for a long time bush chisels had their cuts wedged in place, such wedging showing in many respects an improvement over earlier types of fastening. The difficulty was that under the constant shock of the tool in use there was a continuous loosening tendency and in attempting to keep the cuts tight in the head, the thin flat wedges were over-driven expanding the jaws of the head and eventually rendering it useless. The wedging of the cuts also involved a necessity of holding the cuts against displacement by the wedge and while holding means were devised, these also produced elements of difficulty because if they protruded beyond the sides of the head they were eventually a victim of an accidental stroke of the hammer in tightening the wedge. All these and various other difficulties are well known to the trade and have been the subject of various efforts to overcome them.

My present invention involves certain principles of construction which without detracting from the original utility of the bush chisel as such makes it a highly efficient tool and one capable of long and constant service.

As illustrative of my invention I have shown in the accompanying drawing a characteristic tool illustrative of the principles involved and in itself one of great efficiency in use and economy in manufacture. In the drawing:

Fig. 1 is a side elevation of such a bush chisel.

Fig. 2 an enlarged side view of the head.

Fig. 3 a fragmentary section of the head at right angles to Fig. 2.

Fig. 4 an end view of the head.

Fig. 5 a side view of my tapered wedge of cylindric section.

Fig. 6 an enlarged view of the same, and

Fig. 7 is a fragmentary view of a cut showing its notched or channeled end.

My tool comprises a head 1 having a pole 2. The head 1 is recessed as at 3 for receiving cuts as 4. The head 1 is divided by the recess 2 into externally rounded lateral jaws 1¹ into the sides of which are fitted the ends of the bail or handle 5. At the bottom portion of the recess 3 is located a gib 6 adapted to receive the end thrust of the cuts 4. This gib has a rib 7 transversely of the cuts and interengaging the corresponding recess or groove transversely of the set of cuts. The gib 6 is flushed with the side face of the head 1 and held in place by studs 8. One wall of the recess 3 is cut with a groove 9 of slightly conic taper, that is, it is of conic section cut parallel to the cone axis. With this I provide a wedge 10 having a conic face 10¹ correspond to that of the groove 9 and a flat face 10² adapted to bear against the end cut of a set.

Owing to the conic relation between the wedge and the groove the expansion resultants instead of being directly transversely of the jaws is radially distributed. This relieves the head in a remarkable degree from the old spreading tendency of the flat wedge. It enables the wedge to be tightly driven without springing the jaws and necessitating a further and more damaging driving of the wedge.

The gib 6 being flush with the face of the head 1 is in no danger of damage from a mistaken blow intended for the end of the wedge. It is amply sustained by the pins 8 against any dislodgement and in turn through its rib 7 prevents the dislodgement of the cuts 4 while the wedge 10 is being driven. The rib 7 and groove in the cuts may be of any shape or of reversed relation or otherwise formed to provide an interengagement between the gib 6 and the end of the set of cuts 100.

4. The gib 6 also may be held in any convenient way but preferably by means which will permit it to have its ends flush with the face of the head.

5. Bush chisels in accordance with my invention may be of any design or size and adapted to take any number of cuts. The bail 5 pivoted to the sides of the jaws makes an extremely convenient way of steadyng the 10 chisel and various other features and improvements may be designed, modified or combined, all without departing from the spirit of my invention.

What I therefore claim and desire to secure by Letters Patent is:—

1. In a bush chisel or like tool, a head having a two jaw recess for the cuts, the side walls of the recess being vertical, one wall of said recess having a horizontal transverse 20 groove of rounded cross section, a set of cuts disposable therein and having recessed ends, a wedge of conic sectional form for said groove having a flat face adapted to bear on one side of the cuts to wedge them in the head, 25 a gib in the bottom of the recess and disposed for bearing on the cut ends, said gib having a rib disposed transversely of the cuts to engage the recessed ends thereof.

2. In a bush chisel or like vertical impact 30 tool, a head having a cut receiving open sided recess defined by opposite jaws having flat parallel inner faces forming the side walls of the recess, one of said walls having a horizontal transverse open groove of rounded 35 and tapered cross section extending across the wall face to the open sides thereof, a set of flat face cuts disposed with their ends in said recess between said jaw faces, and a wedge of half conic section fitting said tapered groove 40 and having a flat cut contacting face maintained parallel with the planes of the cut faces and cut ends and at right angles to the vertical axis of impact of said tool.

In testimony whereof I affix my signature.

PUTNAM P. BICKNELL.
